C. S. Attorney.

UNITED STATES PATENT OFFICE.

JACOB MERZ, OF CHICAGO, ILLINOIS.

LIFTING-JACK.

1,201,602.

Specification of Letters Patent. Patented Oct. 17, 1916.

Application filed August 30, 1915. Serial No. 47,933.

To all whom it may concern:

Be it known that I, JACOB MERZ, a citizen of the United States, and residing at Chicago, county of Cook, and State of Illinois, 5 have invented a certain new and useful Improvement in Lifting-Jacks, of which the following is a specification.

This invention relates to lifting jacks, designed especially for handling motor vehicles during the operation of effecting repairs thereto. As is well known, there is now on the market a wide variety of such vehicles ranging in type from "low bed" to "high bed" cars, these terms being significant of the position of the running gear relative to the road bed. The lifting jacks now in general use are not universally applicable to the handling of these various types of vehicles, the defect residing in the 10 fact that the standard, of a given jack, is either too long to permit proper positioning of the device beneath a low bed car, or too short to effect the necessary elevation of high bed cars. The requisite adaptation of such devices to these various types of vehicles is best attained by forming the jack standard in a plurality of sections to be brought into action successively, desiderata, in such constructions, being that the lifting 15 force of the jack be applied in a direct axial line throughout the several sections, and that the lifting strength of such standard be uniform throughout its whole length, and while it has been proposed, heretofore, to 20 provide a jack with a sectional standard, these prior devices have, in so far as I am aware, failed to meet one or another of the above noted requirements, and, furthermore, are objectionable as a result of being complicated and, therefore, expensive and impracticable.

This invention has for its objects, therefore, to provide a comparatively simple, inexpensive jack having a sectional standard 25 whose component sections may be readily brought into play at will; one wherein the lifting force is properly exerted in a direct line; and one in which there is presented, in effect, a continuous unbroken standard 30 whose lifting force is applied uniformly throughout the whole length of its several sections.

With these and other objects in view, the invention comprises the novel features of construction and combination of parts more 55 fully hereinafter described.

In the accompanying drawings: Figure 1 is a side elevation of a lifting jack embodying the invention; Fig. 2 is a top plan view partly in section, the section being taken on 60 the line 2—2 of Fig. 1; Fig. 3 is a vertical sectional elevation, the section being taken on the line 3—3 of Fig. 2, and viewed in the direction of the arrow; and, Fig. 4 is a view similar to Fig. 3, showing certain of 65 the parts in a different position.

Referring to the drawings, it will be seen that the device embodies a vertical casing 1 having a base 2, and provided, in one of its side walls, with a vertical slot 3 which, at 70 its lower end, extends horizontally rearward as at 4, there being formed in the casing and in rear of the slot a vertical chamber or compartment 5 for a purpose which will hereinafter appear.

Arranged for vertical longitudinal movement in the casing is a standard section 6 equipped, at its upper end, with a jack head 7, and, at its lower end, with a dowel 8, there being provided along the front edge 80 of said standard a series of ratchet teeth 9 disposed and arranged for engagement by a lifting pawl 10 and a retaining pawl 11, while arranged in the casing is a leaf spring 12 folded around a retaining pin 13, and 85 having one of its arms engaging a pin 14 on the pawl 10, and its other arm engaging a similar pin 15 on the pawl 11, and exerting its tension to throw the pawls into engagement with the teeth 9.

Pivoted at a suitable point in the casing is an operating lever 16 having pivotal connection, at its inner end, at 17, with the lower end of the lifting pawl 10, while the pawl 11 is pivoted, at its lower end, in the 95 casing at 18, the relation of the pivotal axes of the various parts and the relative lengths of the pawls being such that the upper or active ends of the pawls will engage the ratchet 9 at a common point when the lever 100 16 is at the limit of its downward or lifting stroke.

Normally housed within the chamber or compartment 5 is a second or auxiliary

standard section 19 provided, at its upper end, with a socket or recess 20 to receive the dowel 8, and, adjacent its lower end, with a lateral pin disposed to project outward 5 through the slot 3-4 and equipped, at its outer end, with a milled head 21, there being formed on the front edge of the section 19 a series of teeth 22 disposed and arranged to form a continuation of the ratchet 9, and 10 for engagement by the pawls 10 and 11, as presently explained.

Disposed within the casing at one side of the standard actuating mechanism (shown by dotted lines in Fig. 1), is a trip 15 member or plate 23, formed to provide a lower finger 24 and an upper finger 25 positioned for engagement respectively with the pins 14 and 15, there being also pivoted in the casing a reversing lever 26 having a 20 cam portion 27 disposed for engagement as at 28 with the lower end of the plate 23.

In the operation of the device, suitable manipulation of the operating lever 16 will cause the pawl 10 to feed the jack standard 25 upward through engagement of said pawl with the teeth 9, as will be readily understood. As the standard advances, and during the return stroke of the pawl 10, when the lever 16 is swung upwardly, retrograde 30 movement of the standard is prevented, through engagement of the pawl 11 with the rack 9, as usual. After the standard section 6 has been advanced to the limit of its movement, should further elevation of the work 35 being handled be necessary, the second or auxiliary section 19 of the standard is moved forwardly from its compartment 5 and upwardly to position beneath the section 6, as illustrated in Fig. 4, this movement of the 40 section 19 being effected manually by grasping and suitably manipulating the head 21 to effect movement of the part 19, it being apparent that, during this operation, the pin traveling in slot 3-4 will guide the section 19 to proper position beneath the section 6, and for the dowel 8 to enter and engage the socket 20. By a further manipulation 45 of the operation lever 16, the pawls 10 and 11 will be actuated for feeding the section 19 upwardly as a continuation of section 6, as is obvious, and whereby the vehicle or other work being lifted by the jack may be brought to the desired elevation. When it is desired to lower the jack stand- 55 ard, the reversing lever 26 is moved downwardly in the direction indicated by the arrow in Fig. 1, whereby a leaf spring 29 arranged in the casing will throw the trip plate 23 rearwardly, causing the finger 25 60 to engage pin 15 and move the pawl 11 out of engagement with the rack 9-22. When the lever 16 is now manipulated, the standard will follow pawl 10 downwardly until pin 14 strikes behind the finger 24 and thus

produces a camming action, which will 65 throw the pawl 10 out of engagement with the rack, and, at the same time, rock the plate 23 for moving the finger 25 rearwardly and permitting the pawl 11 to hold the standard during the return upward stroke 70 of pawl 10. Thus provision is made for feeding the standard downward one tooth at a time to lower the work being handled by the jack to its normal position.

It is to be particularly noted that under 75 this invention provision is made for bringing into action at will an auxiliary standard section which, when in operation, forms in effect a part and a continuation of the main section 6, and further that the lifting and 80 retaining pawls included in the actuating mechanism are so arranged and operated that they both engage at the same side of the standard, thus rendering necessary the formation of teeth upon one side only of 85 the latter. It will also be noted that under this construction the several sections of the standard operate in a direct axial line, and further that, through the endwise abutment of the sections relatively, there is no weakening 90 of the standards at the joints, and that, in consequence, the lifting force applied will be uniform throughout the whole length of the sectional standard.

It is obvious that various changes may 95 be made in the details of construction without departing from the spirit of this invention. It is, therefore, to be understood that this invention is not to be limited to the specific construction shown and described. 100

Having thus described the invention, what is claimed is:

1. A lifting jack comprising a sectional standard, said sections being adapted for endwise abutment and to stand in axial alinement; whereby the lifting force of the standard is applied uniform throughout the 105 whole length of its several sections.

2. A lifting jack comprising a sectional standard, said sections being normally disconnected and adapted for assemblage to abut endwise and stand in axial alinement; whereby the lifting force of the standard is applied uniform throughout the whole 110 length of its several sections.

3. A lifting jack comprising a pair of standard sections normally disconnected and disposed laterally one of the other, means for moving the second of said sections into position in axial alinement with 120 the advance section, and actuating means for advancing said sections successively and in continuation one of the other.

4. A lifting jack comprising a casing having a lateral compartment, a vertically movable standard section in said casing, actuating means for advancing said section, and a second section normally disposed in said 125

compartment and operatively arranged to be brought into line with and form a continuation of the first section.

5. A lifting jack comprising a pair of standard sections normally disposed in juxtaposition, the second of said sections being movable to a position in axial alinement with

the advance section, and actuating means for advancing said sections successively and in continuation one of the other.

13

In testimony whereof I affix my signature this 3rd day of August, 1915.

JACOB MERZ.
